UNITED STATES PATENT OFFICE.

FERDINAND FIECHTL, OF CHERRYVALE, KANSAS.

CHARGING CAR.

1,423,314.

Specification of Letters Patent. Patented July 18, 1922.

Original application filed January 28, 1921, Serial No. 440,761. Divided and this application filed July 12, 1921. Serial No. 484,158.

To all whom it may concern:

Be it known that I, FERDINAND FIECHTL, a citizen of the United States, residing at Cherryvale, in the county of Montgomery 5 and State of Kansas, have invented certain new and useful Improvements in a Charging Car, of which the following is a specification.

This invention relates to new and useful improvements in a charging car for vertical 10 smelting furnaces.

One object of the invention is to provide a charging car which is moveable over the retorts of a smelting furnace whereby ore or other material, may be delivered to one of 15 the retorts, or to a plurality of them at the same time.

The car herein shown is illustrated in the application on a smelting furnace filed by me in the United States Patent Office on 20 January 28th, 1921, under Serial Number 440,761, the present application being in the nature of a divisional application to the one above identified. In smelting ore in a fur-

nace of the character disclosed in said original application, it is necessary to partly fill 25 the retorts with low grade ore, or ashes, for the reasons stated in the specifications of said application, and then deliver the high grade ore into the retorts. This can be most 30 conveniently done by means of a specially designed charging car herein specifically described.

With the above and other objects in view 35 this invention has particular relation to certain novel features of construction, operation, and arrangement of parts, an example of which is given in this specification, and illustrated in the accompanying drawings, wherein:—

40 Figure 1 is a fragmentary side view of a furnace showing the charging car thereon.

Figure 2 shows a transverse sectional view, taken on the line 2—2 of Figure 1, and

45 Figure 3 is a plan view of the car.

Referring more particularly to the drawings, the numeral 1 designates the furnace as a whole, which is preferably constructed of tile, and has the vertical retorts 2, 2, arranged in rows to facilitate the charging 50 thereof.

Mounted on the furnace is a track formed of rails 3, 3 on which the charging car 4 travels. This car is composed of a suitable body which is separated into end compartments by means of the transverse partition 5.

These compartments have their respective down spouts 6, 6 and 7, 7 which are hopper-like in form. These respective spouts are 60 controlled by the gates 8, 8 and 9, 9.

One of the compartments of the charging car contains ashes or low grade ore and in filling the retorts, said ashes or low grade ore are first admitted so as to fill up the retort to the level of the top of the cooling chamber, at the bottom of the retort, and the remainder of the retort is filled up with high grade ore. The lower part of each retort is filled with ashes or low grade ore for 70 the reason that it is at all times comparatively cool and the temperature thereof is never sufficiently high to melt the ore.

The car has suitable carrier wheels 10, which run on the tracks 3, so as to bring the 75 car over any of the retorts desired.

What I claim is:—

1. A furnace charging car including a suitable body, a transverse partition separating the body into end compartments, a pair 80 of hoppers into which each compartment is formed, each hopper being extended downwardly forming a down spout and a gate controlling the discharge of material through each down spout. 85

2. A furnace charging car including a body, a transverse partition separating the body into two compartments, each compartment being formed into two hoppers, each hopper extended downwardly forming a 90 down spout, a slideable gate controlling the discharge of material through each down spout, and carrier wheels upon which the car is mounted.

In testimony whereof I have signed my 95 name to this specification in the presence of two subscribing witnesses.

FERDINAND FIECHTL.
